UNITED STATES PATENT OFFICE.

EDGAR F. HEISER, OF KINGSTON, MISSOURI.

CYLINDER-REBORING DEVICE.

1,097,318.

Specification of Letters Patent.

Patented May 19, 1914.

Application filed February 11, 1914. Serial No. 818,038.

To all whom it may concern:

Be it known that I, EDGAR F. HEISER, a citizen of the United States, residing at Kingston, in the county of Caldwell and 5 State of Missouri, have invented a new and useful Cylinder-Reboring Device, of which the following is a specification.

This invention relates to devices for use in metal-working, and particularly to tools 10 and operating means therefor for truing out cylinders.

The principal end in view is to devise an improved method of boring out or reshaping the interior of hollow cylinders, and also to 15 provide a mechanism which will be adapted for hand operation in connection with engine cylinders, as, for example, in motor-car shops, where it is often desired to shape out the interior of cylinders properly with 20 out requiring the mounting of the engine in a power machine.

It is therefore my object to devise improved means for mounting the cutting tool within the engine cylinder, together with 25 provision for centering the tool-carrying means accurately within the cylinder. This provision for insuring the central alinement of the tool-carrying means comprises a pair of circular blocks so tapered and bored as to 30 fit cylinder bores of slightly varying diameter and also to provide bearings for accommodating the tool-carrying shaft while the latter is being centered; after this centering operation, the bearing members 35 proper of the tool-carrying shaft are clamped in position, the centering blocks being removed and the tool-carrying shaft installed in working position.

The invention will now be described more 40 particularly in connection with the accompanying drawing showing one form of means which I have devised for carrying out the aforesaid object, after which those features of my improvements deemed to be 45 novel will be particularly specified in the appended claims.

In the drawing Figure 1 is a perspective view of the device; Fig. 2 is a central longitudinal section of the same in working relation 50 to a cylinder; and Fig. 3 is a sectional detail showing the manner of mounting and adjusting the cutting tool, and Fig. 4 is a fragmentary perspective view of the same portion of the device. Fig. 5 is a sectional detail of a portion of the tool-carrying shaft and one of the adjustable bearings.

In the drawing, the cutting tool 2 is illustrated as carried by a shaft 4, which also operates as a feed-bar, being threaded at one end, and provided at its opposite end with a transverse bore 6 for accommodating a crank arm 8 which is clamped adjustably to the shaft 4 by means of a set screw 10. The tool 2 is also adjustably mounted by having its shank received in a transverse bore 12 in the shaft 4 against the end of an adjusting screw 14, the tool being fixed in adjusted position by means of a clamping screw 16 which engages the shank of the tool through an opening 18 at right angles to the bore 12. This form of tool, however, and the manner of mounting the same, are not essential to the invention, but any equivalent cutting devices, such as may be carried by the shaft 4, may be employed.

The bearing supports for the tool-carrying shaft 4 comprise a bearing bracket 20 and a plate 21. The bracket 20 is illustrated as a goose-neck frame terminating in a split bearing 22 provided with lugs 24 80 whereby the snugness of the bearing fit may be conveniently adjusted by a clamping screw 26, to the end that all vibration or chattering of the tool-carrying shaft 4 may be avoided. The plate 21 is formed with a 85 flat clamping surface on one of its faces and with a boss 28 on its opposite face about the threaded bore 31 provided for the threaded end of the shaft 4. The bearing for the threaded end of the shaft 4 is also split as 90 shown, and the boss 28 provided with lugs 30 and a clamping screw 32 for regulating the tightness of the bearing. Both of the bearing members 20 and 21 are provided with slots 34 for receiving bolts 36 where 95 by the members may be secured in fixed relation to the cylinder 38 which is to be rebored.

For the purpose of locating the tool-carrying shaft 4 with its axis alined centrally 100 with the center line of the cylinder 38, a pair of auxiliary bearing blocks or centering devices 40 is provided. Each block 40 is bored to fit the shaft 4, and its outer edge is of slightly conical form, tapering from a diameter slightly less to a diameter slightly 105 greater than that of the average diameter of cylinder to be operated upon.

In the use of the device, both heads of the cylinder are removed and the centering 110 blocks 40 are fitted into the opposite ends of the cylinder bore, as illustrated in Fig. 2.

The bearing members 20 and 21 are loosely bolted in approximately the position shown, and the shaft 4 is then passed through the bearing 22, the blocks 40 and into the threaded boss 28, the blocks 40 thereby causing the axis of the shaft 4 to assume a position in accurate alinement with the axis of the cylinder bore, and at the same time bringing the bearing members 20 and 21 into the correct position for supporting the shaft in said alinement. The bearing members 20 and 21 are next clamped by the bolts 36 in fixed position and the shaft 4 is then withdrawn in order to remove the centering blocks 40, after which the boring tool 2 is applied to the shaft 4 and the latter then placed in operative position to bring the tool within the cylinder. After adjusting the tool properly, operation of the crank causes 10 the tool to cut along the interior surface of the cylinder and at the same time be fed lengthwise therein, due to the engagement of the threaded end of the shaft 4 with the threaded bore 30 of the bearing member 21, 15 and the shaft being maintained always in perfect alinement centrally in the cylinder because of the previous accurate alinement of its bearings insures that the cutting of the tool will be carried out accurately about 20 the axis of the cylinder bore. After the tool has been fed entirely through the cylinder, the shaft may be retracted and the operation repeated as often as may be necessary, with the cutter advanced slightly by 25 adjustment of the screws 14 and 16.

From the foregoing it will be apparent that I have devised a simple and effective means for carrying out the objects of my invention, and while I have illustrated and 40 described what now appears to be the preferred form thereof, I reserve the right to such changes and modifications as may fairly fall within the scope of the appended claims.

45 I claim:

1. The herein-described method of positioning and mounting a cutter for re-boring cylinders which consists in providing temporary bearings for the cutter shaft inside 50 the cylinder to locate the axis of said shaft in alinement with the axis of the cylinder bore, and then providing fixed bearings outside the cylinder for the shaft as alined.

2. The herein-described method of positioning and mounting a cutter for re-boring cylinders which consists in providing adjustable bearings for the cutter shaft outside the cylinder and temporary centering bearings for said shaft inside the cylinder 55 to locate the axis of the shaft in alinement with the axis of the cylinder bore, mounting said shaft in said bearings and thereby positioning said adjustable bearings, and then

fixing said adjustable bearings in adjusted position and removing the temporary bearings. 65

3. A device for re-boring cylinders comprising a cutter-carrying shaft, adjustable bearings for carrying said shaft, auxiliary bearings adapted to be positioned in the 70 cylinder bore for alining the shaft axially with said bore, and means for fixing said adjustable bearings after said shaft has been alined.

4. A device for re-boring cylinders comprising a cutter-carrying shaft, adjustable bearings for carrying said shaft, auxiliary bearing-blocks bored to fit said shaft and adapted to fit within the cylinder bore for alining the shaft axially with said bore, 80 and means for fixing said adjustable bearings after said shaft has been alined. 75

5. A device for re-boring cylinders comprising a cutter-carrying shaft, adjustable bearings for carrying said shaft, auxiliary bearing-blocks bored to fit said shaft and slightly tapered to fit within the opposite 85 ends of the cylinder bore for alining the shaft axially with said bore, and means for fixing said adjustable bearings after said 90 shaft has been alined.

6. A device for re-boring cylinders comprising a cutter-carrying shaft, adjustable bearings for carrying said shaft, frusto-conical auxiliary bearing-blocks bored to fit 95 said shaft and of an average diameter corresponding to that of the cylinder bore for fitting therein and alining the shaft axially therewith, and means for fixing said adjustable bearings after said shaft has been 100 alined.

7. A device for re-boring cylinders comprising a cutter-carrying shaft, adjustable working bearings and auxiliary shaft-centering bearings carried by said shaft, said auxiliary bearings being adapted to fit within the cylinder bore and thereby center the shaft and position the adjustable working bearings, and means for fixing said adjustable bearings after the shaft has been 110 centered. 105

8. A device for re-boring cylinders comprising a cutter-carrying shaft, adjustable bearings for carrying said shaft and provided with bolt-receiving slots for securing 115 the same in position, auxiliary bearings adapted to be positioned in the cylinder bore for alining the shaft axially with said bore, and bolts for engaging the slots of said adjustable bearings to fix said adjustable bearings in working position after the shaft has been alined. 120
